UNITED STATES PATENT OFFICE.

ADOLPH P. GUSTAFSON, OF CHICAGO, ILLINOIS, ASSIGNOR TO M. SCHULZ CO., OF CHICAGO, ILLINOIS.

BELLOWS FOR PNEUMATICALLY-OPERATED MUSICAL INSTRUMENTS.

1,398,730.

Specification of Letters Patent. Patented Nov. 29, 1921.

Application filed May 29, 1918. Serial No. 237,220.

To all whom it may concern:

Be it known that I, ADOLPH P. GUSTAFSON, a citizen of the United States, residing at Chicago, in the county of Cook and State 5 of Illinois, have invented a certain new and useful Improvement in Bellows for Pneumatically-Operated Musical Instruments, of which the following is a full, clear, concise, and exact description, reference being had to the accompanying drawings, forming a part of this specification.

My invention relates to bellows for pneumatically operated musical instruments.

The principal object of the invention is 15 to provide a simple, practical and effective construction of bellows which may be easily and inexpensively constructed and which may also readily be accessible for purposes of adjustment from the front of the musical instrument.

In the accompanying drawings Figure 1 is a front elevation of a bellows for musical instruments embodying my present invention, together with pedals for operating the 25 same;

Fig. 2 is a cross section taken on line 2—2 in Fig. 1;

Fig. 3 is a view of a detail of construction;

Fig. 4 is a cross section taken on line 30 4—4 in Fig. 3; and

Fig. 5 is a view of a modified form of construction.

In the drawings, and especially Figs. 1 35 to 4, inclusive, I show a bellows A consisting of a front member 1, which is usually mounted in a stationary manner in the musical instrument, and a rear member 2 which is hinged at 3 to the front member 1 and 40 adapted to swing back and forth so as to produce the desired variation in wind pressure to operate the musical instrument. A spring 4 is shown acting upon the member 2 tending to maintain the same in a normally forward position so that the bellows 45 may be normally collapsed.

Pedals 5 are shown mounted in front of the bellows A and connecting or operating rods 6 extend rearwardly from the pedals 50 5 for operating the swinging rear member 2, being connected therewith by links 7. Rods 8 are extended between the pedals 5 and the front member 1 and connected with the same for holding said parts in position 55 and permitting the pedals 5 to be swung up-

wardly into position in front of the front member 1.

Valves 9 are provided in the front member 1 and control ports 10 which establish communication between the outside air and the interior of said bellows A. The number of ports 10 may be varied. I have shown four such and have accordingly shown the valve 9 to be of substantial size so as to control by opening and closing all of said ports 10. The valve 9 is preferably provided with a guide pin 11 adapted to fit in a corresponding aperture 12 in the member 1 to guide said valve 9 in its movement to open and close the ports 10. A spring 13 is arranged to act upon the valve 9, tending to hold the same normally in a closed position against the member 1. The spring 12 is held in position by a staple or clip 14 driven into the member 1. The spring 13 is provided at one end with a small loop 15 adapted to fit over and engage the outer end 11a of the pin 11. The valve 9 is preferably in the form of a flat circular disk with a layer 16 of leather or similar material to make a tight joint with the surface of the member 1.

Thus it will be seen that in the operation of the pedals 5 the rear member 2 will be swung back and forth and the operation of the bellows will cause the valves 9 to be moved forwardly and rearwardly so as to open and close the ports 10 in accordance with the requirements of the pneumatic pressure within the same. These valves 9 being on the front of the bellows are readily accessible so that they may be adjusted, repaired or changed as may be required. Furthermore, they are much simpler, more accurate and satisfactory in construction and operation than leather straps which have heretofore been used in this connection.

In Fig. 5 I show the valve 9 applied to the rear member 2. This may be done if desired, although it is preferable to apply it to the front member in order that it may be accessible.

It will be understood that changes and modifications may be made without departing from the spirit of the invention.

What I claim is:

1. In a bellows for player pianos, in combination, a front exposed stationary member having a plurality of ports communicating with the interior of the bellows and a valve mounted entirely on the exposed front 105 110

face of said member and controlling said ports.

2. A bellows having its exposed front member provided with ports communicating with the interior of the bellows and valve mechanism on the front exposed face of said member for controlling said ports, said valve mechanism having a slideable mounting permitting it to open in a forwardly direction.

10 3. In a bellows for player pianos, in com-

bination, a stationary exposed front member and a hidden rear movable member thereon, a plurality of ports in the exposed front member and a valve operating entirely externally of the front member on the 15 exposed face thereof for controlling said ports.

In witness whereof I hereunto subscribe my name this 12th day of March A. D., 1918.

ADOLPH P. GUSTAFSON.
